United States Patent Office.

B. A. HAYCOCK, OF RICHLAND, IOWA.

Letters Patent No. 76,442, dated April 7, 1868.

IMPROVEMENT IN THE LININGS OF FURNACES.

The Schedule referred to in these Letters Patent and making part of the same.

TO ALL WHOM IT MAY CONCERN:

Be it known that I, B. A. HAYCOCK, of Richland, in the county of Keokuk, and State of Iowa, have invented a new and useful Improvement in Lining Furnaces; and I do hereby declare that the following is a full, clear, and exact description thereof, which will enable others skilled in the art to make and use the same, reference being had to the accompanying drawing, forming part of this specification.

This invention relates to a new and improved method of lining the fireplace or furnace of stationary steam-boilers; and the invention consists in forming a solid lining of clay within the outer walls, and enclosing the fireplace, as will be hereinafter described.

The drawing represents a front sectional elevation of a steam-boiler arch, with the boiler in plane, the front wall or arch-plate being removed, in order to show the lining to better advantage.

A represents the steam-boiler; B, the outer walls of the arch; C is the lining; D represents the furnace, and E the grate; F, the height of the bridge-wall or back end of the furnace.

The ordinary mode of lining the furnace is to build the sides and bridge-wall up with fire-brick, or with common brick. In many sections of the country the former article cannot be obtained without great trouble and expense, and the latter require to be renewed so frequently, in consequence of their destruction by the heat, that such walls are a constant source of expense. After being long troubled and annoyed by the difficulties incident to this state of things, I tried the experiment of filling in the sides of my furnace with solid clay, with the view of overcoming the difficulty, and have succeeded to my entire satisfaction.

In carrying out my invention, I prepare for filling in the clay by placing a frame, C', on each side of the furnace, forming spaces for the clay, as seen in the drawing. After properly preparing the clay, I fill these spaces full, ramming or tamping down the clay into a solid mass, as seen at C. The frames C' are then removed or burned out, and a fire can be built when the lining becomes a little dry, when, after a short time, the clay will be found to have been thoroughly burned, and to form one solid brick, which withstands the effects of the heat, and obviates all difficulty. The bridge-wall may be formed in the same manner.

The lining or fire-wall thus formed in one mass, having no angles which are exposed to the intense heat to crack off, withstands the effects of the heat for a long time without material injury.

What I claim as new, and desire to secure by Letters Patent, is—

A furnace or fireplace-lining for steam-boilers, formed of clay, substantially in the manner herein shown and described.

B. A. HAYCOCK.
